UNITED STATES PATENT OFFICE.

AUGUST D. COOK, OF LAWRENCEBURG, INDIANA.

DESIGN FOR A WELL-STRAINER.

SPECIFICATION forming part of Design No. 26,800, dated March 23, 1897.

Application filed January 7, 1897. Serial No. 618,418. Term of patent 14 years.

To all whom it may concern:

Be it known that I, AUGUST D. COOK, a citizen of the United States, residing at Lawrenceburg, in the county of Dearborn, State 5 of Indiana, have invented and produced a new and original Design for Well-Strainers, of which the following is a specification, reference being had to the accompanying drawings, showing a part thereof.

10 Figure 1 is a perspective of a well-strainer embodying my design. Fig. 2 is a vertical sectional view of the same, the strainer being exaggerated. Fig. 3 is a horizontal or transverse section of the strainer, these views being deemed necessary to illustrate my design.

15 The leading feature of my design consists in a series of vertical rows of transversely-disposed elongated slits or openings formed in the wall of the strainer, which strainer, as 20 is well known, is tubular. The slits or openings are formed at regular intervals and at right angles to the external surface of the strainer. The outer portions of these slits or openings, say for about a quarter of their depth, have their upper and lower surfaces 25 parallel, but beyond said point the surfaces are gradually diverged in straight lines at an angle of about forty-five degrees.

A represents the wall of the strainer; B, the outer portions of the slits or openings; 30 C C, the parallel surfaces of the slits or openings, and D D the flared surfaces of the same.

What I claim is-- 35 The design for well-strainers herein shown and described.

In testimony whereof I affix my signature in presence of two witnesses.

AUGUST D. COOK.
